UNITED STATES PATENT OFFICE

2,059,501

PUNCH PRESS FOR CELL CASE MACHINES

Dan R. Vail, Evanston, Ill., assignor to Paper Partitions, Inc., Chicago, Ill., a corporation of Illinois

Application June 12, 1935, Serial No. 26,142

12 Claims. (Cl. 164—19)

This invention relates to a device for cutting slots of a desired length in paper webs for the production of punched strips for cell cases or partition cells.

5 More specifically, this invention relates to a punch press mechanism for cell case machines which can be readily adjusted to cut slots in paper webs of any desired length without changing the punching mechanism.

10 It is customary in machines for manufacturing cell cases to pass one or more webs of paper through a punch press mechanism so that slots may be formed in the webs for the production of punched strips which may be mechanically or manually interlocked with each other to form the partition cell. It is obvious that the length of the slot cut into the web will vary considerably, depending upon the height of the cell case being formed. Furthermore, the slots may vary 20 widely in relative position to each other depending upon the size of partition cell being formed.

I have now provided a punch mechanism for cutting slots into paper webs which is readily adjustable to vary the position of the slots relative to each other and to vary the length of the slot being cut without requiring the use of different dies.

It is therefore an object of this invention to provide a slot cutting device for paper webs which 30 is capable of forming slots in the web having any desired length and position.

A further object of this invention is to provide a punch press for cell case machines in which the amount of movement between the 35 male and female members of the press can be readily adjusted to cut slots of any desired length.

It is a further object of this invention to provide a punch press for cutting slots in paper webs 40 with knives having sloping cutting edges and regulating the amount of cutting edge to be used by limiting the movement of the press.

A specific object of this invention is to provide a punch press mechanism for cell case machines having a plurality of stationarily mounted cutting knives with sloping cutting edges and a movable female die for receiving said knives together with means for adjusting the movement of said die over said knives.

50 Other and further objects of this invention will be apparent from the following detailed description of the annexed sheets of drawings, which illustrate a preferred embodiment of the invention.

55 It should be understood that many changes

may be made from the illustrated disclosure without departing from the scope of this invention.

On the drawings:

Figure 1 is a fragmentary side elevational view 5 of a punch press according to this invention showing the passage of a web of paper therethrough.

Figure 2 is a horizontal cross-sectional view taken substantially along the line II—II of Figure 10

Figure 3 is a vertical cross-sectional view, with parts in elevation, taken substantially along the line III—III of Figure 1.

Figure 4 is a horizontal cross-sectional view 15 taken substantially along the line IV—IV of Figure 3.

Figure 5 is a fragmentary elevational view 20 of an adjustable eccentric disc which may be used in the apparatus of this invention.

Figure 6 is a fragmentary plan view of a web 25 of paper having slots cut therein by the punch press of this invention.

As shown on the drawings:

In Figures 1 to 4 inclusive the reference numbers 10, 11, 12 and 13 indicate vertical rods or standards on which the punching mechanism is mounted. While four rods have been illustrated, it is obvious that the device may be constructed with the use of one rod only on each 30 side of the machine.

A plate 15, preferably of the shape shown in Figure 4, is secured to the tops of the rods 10 to 13 as shown. This plate 15 is stationary and is provided near the center thereof with two 35 parallel rows of T-shaped grooves 16 and 17 extending across the width of the plate. A plurality of bolts 18 and 19 have the heads thereof seated in the grooves as shown in Figure 1. The shanks of the bolts 18 and 19 extend through 40 the vertical portion of the groove and through the horizontal flanges 20 of the vertical cutting knives 21. Nuts 22 and 23 are threaded onto the bolts 18 and 19 respectively to hold the knives 21 in position. It is obvious that the position of 45 these knives may be readily adjusted by sliding the bolts in the grooves 16 and 17 and that the knives may be locked in adjusted position by tightening the nuts 22 and 23. While three knives 21 have been shown in Figures 3 and 4, 50 it is obvious that one or any number of knives may be used. Each knife 21 has a cutting edge 24 sloping from the horizontal as shown in Figure 1. Each knife 21 likewise has a flared-out V-portion 25 extending along the long side thereof. 55

This flared-out V-portion is for punching a V into the paper web as will be hereinafter described.

A plate 26 is slidably mounted on rods 10 to 13 inclusive, as shown. The plate 26 has a plurality of set screws 27, 28, 29 and 30 threaded therethrough for supporting a platen 31 in which the female dies are mounted, as will be hereinafter described.

10 A plurality of bolts 32, 33, 34 and 35 are inserted through holes in the corners of the platen 31 adjacent to the set screws 27 to 30. The bolts 32 to 35 extend through holes in the plate 26 and receive nuts 36 for securing the platen 31 to the plate 26. It is obvious that the set screws 27 to 30 may be adjusted to vary the position of the platen 31 relative to the plate 26. The central portion of the platen 31 is preferably cut away as indicated at 37 in Figures 1 and 3 to provide an opening therethrough. The punchings from the paper web can fall through this opening.

The platen 31 has formed therein, on each side of the opening 37, T-shaped grooves 38 and 39 for receiving the heads of bolts 40 and 41. 25 The bolts 40 and 41 extend through the ends of the female die members 42 and receive nuts 43 which may be tightened to secure the dies in position on the platen 31. The dies 42 are adapted to receive the cutting knives 21 and are thus provided with a slot opening 44 and a V-shaped opening 45 in communication therewith as shown in Figure 2. The dies 42 are readily adjusted by loosening the nuts 43 and sliding the dies together with the bolts 40 and 35 41 along the grooves 38 and 39. When the nuts 43 are tightened on the bolts 40 and 41 the dies are securely held in adjusted position.

The platen 31 carries two U-shaped bands 46 and 47 on each side thereof as shown. The web 40 of paper W (Figure 1) is directed under the bands 46 and 47 and over the dies 42 by feed rollers R and R'. The bands 46 and 47 act as strippers as will be hereinafter described.

The plate 26, as shown in Figures 1, 2 and 3, 45 carries on each side thereof a laterally extending pivot 48 and 49. Links or connecting rods 50 and 51 are pivotally mounted on the pivots 48 and 49 at one end thereof. The other ends of the links 50 and 51 are pivotally mounted on eccentrics 52 and 53 (Figure 3). The eccentrics are keyed to a shaft 54 driven by a pulley 55 which in turn is driven by a belt 56 (Figure 1) from a suitable source of power.

When the eccentrics 52 and 53 are rotated the 55 connecting rods 50 and 51 slide the plate 26 up and down along the rods 10 to 13. The female dies 42 are thus raised over the cutting knives 21 and the web W is punched as shown in Figure 6 with slots S having V-shaped ends E.

60 On the downward stroke the plate 26 is lowered, thereby carrying the dies 42 away from the knives 21. The stripping bands 46 and 47 carry the web W downward with the dies thereby removing the web from the knives 21. The web W is then advanced a suitable distance by the rollers R and R' and on the succeeding up-stroke the punch press mechanism forms a new set of slots therein.

The length of the slots is readily adjusted by a manual setting of the set screws 27 to 30. 70 If these set screws are lowered and the nuts 36 tightened around the bolts 32 to 35, it is obvious that the up-stroke of the plate 26 will not carry the dies 42 entirely over the knives 21. As a result the lengths of the slots S in the web W 75 will be shortened because that portion of the

cutting edge 24 of the knives 21 which is not seated in the dies 42 will not be effective. It is therefore evident that the raising and lowering of the platen 31 by the set screws 27 to 30 will effect a variation in the length of the slots S. 5

As pointed out above, the cutting knives 21 and the dies 42 are readily adjusted relative to each other by sliding the same along in the T-shaped grooves provided in the stationary top plate 15 and in the platen 31. When adjusting 10 the position of the knives and dies, it is preferable to seat the dies around the knives and move each knife together with its corresponding die so that when the same are tightened into position they will be in exact alignment. 15

As shown in Figure 6, the ends of the slots S are enlarged or flared outwardly as at E. The provision of this enlarged portion is desired because when the web W is cut along the line L to produce the cell case strip the enlarged portions E of the slots S permit easy interlocking of the strip with other strips. The enlarged portions E serve as guides to the slots S. 20

In Figure 5 there is shown another means of adjusting the movement of the lower dies 42 25 which may be used together with the set screws 27 to 30 or in place of these set screws. As shown in Figure 5 a disc 60 for mounting on a drive shaft (not shown) is provided with a T-shaped groove 61 extending thereacross. A cross-head 62 is slidably mounted in this groove 61 and may be locked in position therein in the usual manner. The cross-head 62 carries a pivot 63 on which is pivotally mounted a connecting rod 64. It is obvious that the movement of the plate 30 26 of the punch press mechanism may be varied by an adjustment of the cross-head to vary the eccentric throw of the disc 60. The eccentric disc 60 may be used to roughly adjust the movement of the dies 42 while the set screws 27 to 30 may be used as micrometer adjustments for this movement. 35

I am aware that many changes may be made and numerous details of construction may be varied through a wide range without departing 45 from the principles of this invention, and I, therefore, do not purpose limiting the patent granted hereon otherwise than necessitated by the prior art.

I claim as my invention:

1. A punch press mechanism comprising a cutting knife having a sloping cutting edge, a female die for receiving said knife, means for moving said die over said knife for seating the knife in the die, and means to adjust the amount of movement for regulating the length of cut to be made by the knife. 55

2. A punch press mechanism comprising a male cutting knife having a sloping cutting edge, a female die for receiving said knife, means for feeding a web of paper over said die, means for moving said female die over said knife for seating the knife in the die, and means to adjust the amount of movement for regulating the length of cut made by the knife in said paper. 60

3. A punch mechanism comprising a frame structure, a top plate stationarily mounted in said frame structure, cutting knives having sloping cutting edges adjustably mounted in said plate, a lower plate slidably mounted on said frame structure, female dies adapted to receive said cutting knives, adjustably mounted on said plate, and means to regulate the movement of said plate to vary the length of cut by said knives. 70

4. A punch mechanism comprising a frame 75

- structure, a plate securely mounted on top of said frame structure, a T-shaped groove in the bottom of said plate, cutting knives having sloping cutting edges, bolts extending from said 5 groove for securing said knives to said plate, a lower plate slidably mounted on said frame structure, female dies carried by said plate for receiving the cutting edges of said knives, and means for regulating the movement of said dies 10 to vary the cuts made by said knives.
5. A punch press comprising a frame structure, a plurality of knives vertically mounted thereon, said knives having cutting edges sloping from the horizontal, female dies slidably 15 mounted in said frame for receiving said knives, means for feeding a web of paper over said dies, means for raising the dies and paper over the knives to cut slots in the paper, and means for regulating the amount of movement of said dies 20 to produce a slot of the desired length in the paper.
6. A punch press mechanism for cell case machines to cut slots in paper webs, comprising a frame structure, a plate secured to the top of 25 said frame structure, said plate having a pair of parallel T-shaped grooves cut in the bottom thereof near the center of the plate, bolts seated in said grooves, a plurality of knives secured to said plate by said bolts, said knives having cutting edges sloping from the horizontal, a lower plate slidably mounted on said frame, a platen carried by said lower plate, female dies for receiving the knives secured on said platen, means for raising and lowering said plate toward said 30 knives, and means for raising and lowering said platen relative to said slidable plate for adjusting the amount of insertion of the knives into the dies to thereby regulate the lengths of the slots being cut.
- 40 7. A punch press mechanism for cell case machines to cut slots in paper webs comprising a frame structure, a plurality of cutting knives secured to the top of said frame structure and extending vertically downward therefrom, said knives having cutting edges sloping from the horizontal, a plate slidably mounted on said frame structure, a platen carried by said plate in spaced relation therefrom, set screws for adjusting the position of said platen relative to said 45 plate, female dies adjustably mounted on said
- platen for receiving said knives, and means for raising said plate to carry the dies over said knives whereby an adjustment of the position of the platen relative to the plate will effect a variation in the length of slots cut by said 5 knives.
8. A slot cutting device comprising a frame, knives vertically suspended from the top of said frame, said knives having cutting edges on the bottoms thereof sloping from the horizontal, female dies slidably vertically on said frame for receiving said knives, stripper bands disposed over said dies, means for feeding a web of paper over said dies and under said stripper bands and means for adjusting the movement of said dies 10 to vary the length of slot cut into the paper by the knives.
9. A slot cutting device comprising a frame, knives vertically suspended from the top of said frame, said knives having cutting edges on the bottoms thereof sloping from the horizontal and having flared out V edges on the long sides thereof, female dies slidably vertically on said frame for receiving said knives, and means for adjusting the amount of movement of said dies 15 to vary the amount of insertion of said knives therein.
10. The method of forming slots in paper webs which comprises passing a paper web over a female die, moving said die with the web thereon against sloping cutting edges and regulating the amount of movement to produce slots of various lengths.
11. The method of forming slots in paper webs which comprises passing a paper web over a female die and under a stripper carried by the die, moving said die with the web thereon against sloping cutting edges, regulating the amount of movement to produce slots of various 20 lengths in the web and withdrawing said die and stripper for removing the web from the cutting edges.
12. The method of forming slots in webs which comprises passing a web over a female die, moving said die with the web thereon against a sloping cutting edge and regulating the amount of movement to produce a slot of the desired length in said web, said movement being the normal cutting action of the method.

DAN R. VAIL. 50

CERTIFICATE OF CORRECTION.

Patent No. 2,059,501.

November 3, 1936

DAN R. VAIL.

It is hereby certified that error appears in the printed specification of the above numbered patent requiring correction as follows: Page 2, first column, line 51, after the reference numeral "54" insert the words rotatabl supported in bearing supports such as 54a. The shaft 54 is; and that the sa Letters Patent should be read with this correction therein that the same may conform to the record of the case in the Patent Office.

Signed and sealed this 12th day of January, A. D. 1937.
